UNITED STATES PATENT OFFICE.

EDWARD T. SHAW, OF PITTSFIELD, MASSACHUSETTS, ASSIGNOR TO GENERAL ELECTRIC COMPANY, A CORPORATION OF NEW YORK.

FAN-MACHINE.

1,295,618.

Specification of Letters Patent. Patented Feb. 25, 1919.

Application filed September 10, 1914. Serial No. 861,120.

To all whom it may concern:

Be it known that I, EDWARD T. SHAW, a citizen of the United States, residing at Pittsfield, county of Berkshire, State of Massachusetts, have invented certain new and useful Improvements in Fan-Machines, of which the following is a specification.

My invention relates to a fan machine in which one or more rotary fans are mounted upon a revolving structure or carrier, and it is concerned more especially with a propulsive action of the rotary fan to revolve the carrier. It is my aim to control and regulate the rate of revolution of the carrier effectively: to secure rapid starting and speeding up thereof to its desired normal speed when the fan is started up or brought into action upon the air; and to provide for convenient variation of the normal speed by way of adjustment. Other advantages obtainable in connection with my invention include efficiency, simplicity, reliability, and convenience in action and operation; thorough and controllable distribution of the air acted on; and comparative simplicity, durability, and ruggedness of construction. The principles and character of the invention will appear from the following discussion and from the subsequent description of particular embodiments, while its scope is indicated in my claims.

In accordance with my invention, I control and regulate the speed of the revolving carrier by varying or regulating the propulsive effect or torque produced upon it by the rotary fan. As the speed of revolution ordinarily desired for the carrier is comparatively low and the inertia and static friction of the revolving parts usually considerable, it is often impossible to start the carrier into revolution from a state of rest without an effective torque so high that it would ultimately produce a speed far greater than is desirable. By my invention it is practicable to employ a higher torque for starting than is necessary to maintain the normal speed when once attained or even to start successfully,—so high, in fact, that the period required to bring the parts into revolution and up to speed from a state of rest is very short indeed,—and also to regulate and adjust the carrier speed for normal running with great delicacy. I secure both the quick starting and the regulation of the speed of the carrier for normal running automatically, by pro-

viding means for suitably varying the torque controlled by the speed itself.

As the torque produced by the rotary fan upon the carrier depends on the blade area and pitch, on the speed of rotation of the fan, on the position of the fan on the carrier with reference to the axis of revolution of the latter, and on the general or prevalent path and direction of the blast of air produced by the fan with reference to the carrier and its axis,—these last three factors determining the lever arm of the air blast, or rather of the reaction due to it,—I may produce the desired variation of the torque by changing any one or more of these factors. Ordinarily, however, I prefer not to vary the fan area, pitch, or speed for this purpose, both for reasons of mechanical and electrical simplicity, lightness, and compactness, and because such variations would affect the amount and velocity of the air blast of the fan.

I have herein illustrated and described in detail several simple fan machines in each of which there are two rotary fans directly driven by individual electric motors mounted with them on the revolving carrier, and in which variation in the path and direction of the air blast and shifting of the fan with reference to the axis of the carrier are relied on for varying and regulating the torque. While, however, the mechanisms here shown are the best for the purposes of my invention at present known to me, and while the invention extends to their novel features and details of operation and construction and combinations and arrangements of parts, the invention is not confined thereto, but can be otherwise carried out and embodied.

In the accompanying drawings, Figure 1 is a side view of a fan machine constructed in accordance with my invention, certain parts being broken away; Fig. 2 is a plan view of one of the fans and the parts immediately associated with it; Fig. 3 is a side view illustrating a somewhat different type of fan machine constructed in accordance with my invention, only the fan and the parts immediately associated with it being shown; Fig. 4 is a corresponding end view; Fig. 5 is a side view of still another type of fan machine embodying my invention, an intermediate portion of a supporting member being broken out and omitted; Fig. 6 is a corresponding mid-section on an enlarged

scale, certain parts (including both fans and their motors) being broken away or omitted altogether; Fig. 7 is a sectional view showing various interior parts of the mechanism 5 as seen from above, this view in a general way corresponding to Fig. 6; Fig. 8 is a fragmentary sectional view similar to the lower portion of Fig. 6, but at a plane of section about 60° from that of Fig. 6; Fig. 9 10 is a fragmentary plan view of part of the mechanism shown in Fig. 7 with certain tension springs added; and Fig. 10 is a fragmentary section at a surface corresponding to the line 10—10 in Fig. 7, the construction 15 being slightly modified.

Referring first to Figs. 1 and 2, it will be seen that the carrier 1 is arranged to revolve about an upright axis 2, and that each of the fans 3 with its electric motor 4 is 20 fixedly but adjustably mounted at the outer end of one of the carrier arms 5. Details of the mounting of the carrier 1 on the axis 2 and of the electrical connections to the motors 4 are omitted to avoid needless confusion of the drawing. It will be seen that the fan axis or shaft 6 extends more or less radially with reference to the axis 2, so that the air acted on by the fan as it rotates is 25 "thrown off" more or less radially when the carrier 1 revolves. In front of the fan 3 is a directing vane 7 whose pivot spindles 8 have bearings in the brackets 9. On the lower spindle 8 is a crank member or arm 10 which carries a centrifugal weight 11, 30 and to a stud on this weight 11 is secured a helical tension spring 12. The lower pivot spindle 8 has also a short sector-like arm 13 carrying studs 14 that are adapted to engage the bracket 9 and serve as stops to 35 prevent the vane 7 from turning one way beyond a position of parallelism with the fan shaft 6 or the other way beyond the position shown. In most cases it will be preferred to make the vane 7 symmetrical 40 with respect to the axis formed by the spindles 8, as shown, so that the air blast shall not tend to turn it either way. While the axis of the spindles 8 is shown vertical so 45 that gravity does not affect the action of any of the parts, the brackets 9 are adjustably secured to the motor casing in such a way that it can be inclined with reference to the vertical so as to make gravity supplement the spring 12 in urging the vane 7 toward the position shown, or even take its 50 place.

When the carrier 1 and the fan 3 are at rest,—the arrangements and adjustments being as shown in the drawing,—the only 55 force acting on the vane 7 is that of the spring 12, and it accordingly assumes the diagonal position shown in Figs. 1 and 2. When the fan 3 is started up, the vane 7 diverts at least a portion of the resulting 60 blast of air sidewise from its radial path

and thus produces a considerable torque on the carrier 1 in the direction indicated by the arrow (Fig. 2). As the carrier 1 is started into revolution and gathers speed, the centrifugal force on the weight 11 overcomes the spring 12 and swings the vane 7 around toward a truly radial position, thus reducing the diversion of the air blast and the torque on the carrier 1 resulting therefrom. If the fan 3 is so adjusted on the arm 5 that its shaft 6 is truly radial, as shown, the final, normal speed of revolution of the carrier 1 will always be that for which equilibrium exists between the spring 12 and the centrifugal force on the weight 11. If, however, the adjustment of the fan 3 is such that the shaft 6 is materially out of the radial position, so that the fan will produce a torque irrespective of the vane 7, the tension on the spring 12 may be made so low that the vane 7 will lie parallel with said shaft and so be totally without effect when the final, normal speed is reached. In either case the general direction of the air blast and the torque on the carrier 1 produced by the fan 3 are varied and regulated by means of the vane 7, the weight 11, and the spring 12 under the control of the speed of revolution of the carrier 1 and independently of the speed of rotation of the fan, so that the torque is high when the fan is started into action on the air and is reduced after the carrier has been brought into revolution and gathered speed.

In Figs. 3 and 4 I have shown a machine in which the general path of the air blast rather than its direction is shifted to vary the torque, but which is otherwise very similar to that of Figs. 1 and 2. As will be seen from Fig. 3, there is beneath the fan 15 a short shaft 16 mounted to oscillate in a bracket structure secured to the fan motor casing, suitable means being provided to limit its movement both ways. From this shaft 16 extends upward an arm 17 carrying a circular baffle vane 18 adapted to swing in front of the fan 15 from the position shown to a position where its center will fall in the plane of the carrier and fan axes. The shaft 16 carries a bevel gear 19 with which meshes a similar gear 20 whose shaft 21 carries a depending arm 22 on which is a centrifugal weight 23. An adjustable tension spring 24 is connected from the arm 22 to the bracket structure. The baffle vane 18 acts under control of the centrifugal force on the weight 23 to virtually shift the path of the air blast without altering its direction, and so varies the torque. The action as regards the starting and regulation of the revolving carrier 25 is very much the same as in the machine of Figs. 1 and 2.

Referring, now, to the electric fan machine shown in somewhat greater detail in

Figs. 5, 6, 7 and 8, it will be seen that there is a hollow member 30 by which it may be suspended from a ceiling or the like, and that the carrier 31 has an enlarged central hub portion 32 in which are ball bearings 33 and 34 whereby it is supported on said member 30 and steadied with reference thereto. (See Fig. 6.) Secured on the member 30 at the upper side of the hub 32 is a stationary canopy 35 that incloses means for transmitting current to operate the fan motors to their supply connections in the revolving carrier and fits down as close as possible to the upper edge of the hub so as to afford the greatest possible protection to these and other interior parts. As shown, the transmission means comprise adjustable brushes 36 whose holders are mounted in the walls of the canopy and contact rings 37 that are insulatively mounted on a sleeve 38 that extends from a transverse web in the hub 32 up around the member 30. Current supply wires 39 extend down through the member 30 to a switch 40 mounted on its lower end and then up and out through a hole 41 to the brushes 36. From the contact rings 37 wires 42 that form the current supply connections to the fan motors extend down through the web above mentioned and out through the arms 43 of the carrier 31, starting coils 44 that rest on the web being interposed in these connections. For alternating current fan motors, these coils will be inductance coils, while for direct current motors they will be merely resistance coils. In either case this location of the coils simplifies and lightens the fan motors and avoids complication in their electrical connections.

The fans 45 with their motors 46 (Fig. 5) are movably mounted at the outer ends of the arms 43 so that they may swing with reference to the carrier 31 in a more or less nearly horizontal plane. As shown, the end of each of the arms 43 is divided or forked to receive a lug 47 on a bracket 48 (Figs. 5 and 7). A conical ended pivot pin 49 at the lower side of the lug 47 seats in a socket in the lower side of the fork, while a pivot pin 50 whose upper end is screwed through the upper side of the fork extends down into a socket in the upper side of the lug 47. The fan and motor are pivoted between arms 51 on said bracket 48 by means of trunnions that engage the holes in the motor casing, so that the fan and motor may be tilted up or down to bring the fan shaft 52 to any desired angle with the horizontal and vary the distribution of the air acted on, a thumb screw 53 in one of the bracket arms (Fig. 5) serving to secure the parts in adjusted position.

While various arrangements can be made, I prefer to obtain the speed controlled variation of the torque produced by a fan 45

on the carrier 31 by means of the movable mounting of the fan and its associated parts without any gravity or spring action or any special centrifugal weight such as set forth in connection with Figs. 1, 2, 3, and 4. As shown, the arms 51 are so located on the bracket 48 that the center of gravity of the fan 45 with its motor 46 and the bracket is eccentric to the axis formed by the pivot pins 49 and 50 (which extends in the same general direction as the axis 30), and the fan shaft axis 52 is also eccentric to said pivot axis 49, 50, and the outer end of the arm 43 is curved so as to allow the pivot 49, 50 to lie well behind the rear side of the arm. (See Fig. 7.)

When the carrier 31 is at rest and the fan 45 is started, the reaction of the air on its blades will swing it around with its associated parts from any position in which it may be till the bracket 48 comes against the rear side of the arm 43, (Figs. 5 and 7). Under this condition, the fan axis 52 will be nearly normal to a line extending from the axis 30 of the carrier 31 through the pivot axis 49, 50, and the torque due to the fan 45 tending to overcome static friction and rotate the carrier in the direction of the arrow (Fig. 7) will be almost the greatest possible, so that the carrier will be brought into revolution and gather speed quite rapidly. The torque on the carrier 31 will remain constant until the moment of the centrifugal force of the pivotally mounted parts about the pivot axis 49, 50 equals and exceeds the moment about said axis due to the fan 45 plus the static friction at the pivots, whereupon said parts will swing outward on said pivot 49, 50 and the torque will diminish. This change in the torque will be at a comparatively slow though progressively increasing rate at first, partly because the distance of the center of gravity of the pivoted parts from the axis of revolution 30 will increase but slowly as said parts swing, and partly because the lever arm of the centrifugal force about the pivot 49, 50 will be initially small and will at first increase quite slowly. The rate of the change will continue to increase until the carrier 31 has reached a fair speed; and then, having reached its maximum, the rate of the change will (for reasons similar to the above) progressively diminish. Assuming that the outward swing of the pivotally mounted parts is not sooner arrested in any way, it will continue with the consequent change in the torque and an accompanying increase in the carrier speed until equilibrium between the centrifugal and fan moments about the pivot 49, 50 is reached. Owing to the inertia of the parts and the rapid acceleration, the carrier may in reality first reach a speed slightly in excess of its final normal speed and then slow down a

little. For such designs and fan speeds as will ordinarily be preferred, the final condition of equilibrium will be with the fan axis 52 in a very nearly radial position and the carrier 31 revolving at a speed still very moderate, so that the air from the fan 45 will be well distributed and will be felt as an agreeable intermittent breeze. By a proper design and arrangement of the parts, it is easy to make the normal carrier speed determined as above set forth quite as low for any practical fan speed as will in practice ever be desired.

While the final, normal speed of the carrier 31 can not be made lower for a given fan speed than under the condition of final equilibrium between the centrifugal and fan moments, by arresting the outward swing of the pivotally mounted parts before this condition is reached the normal carrier speed can be made as much greater than this as desired,—always, of course, within the upper limit fixed by the torque of the fan 45 on the carrier 31 when the fan is in its starting position shown in Figs. 5 and 7. I will now describe means for conveniently adjusting the carrier speed in this way without stoppage of either the carrier or the fans.

As shown in Figs. 5 and 7, the lugs 47 of the brackets 48 have each a crank arm 54 extending within the fork of the corresponding carrier arm 43, and these crank arms are connected by rods 55 within the arms 43 to a common disk like member 56 mounted and arranged so that it may turn freely coaxially with the member 30. As will be seen from Figs. 6 and 8, the disk part 56 is mounted on the reduced upper end of a sleeve portion 57 of an inverted cup-like part 58 keyed fast at 59 in the lower end or side of the carrier hub 32 and is held in place by a disk 60 secured to the end of said sleeve 57 by screws 61. Threaded on the lower end of the hollow member 30 is a normally stationary inverted cup-like adjusting part 62 adapted to enter the part 58, and on the upper side of this part 62 is still another part 63 having an upwardly extending sleeve portion 64 that fits snugly but loosely within the sleeve 57 of the part 58. The ball bearing 34 already referred to rests on the upper side of the adjusting nut part 62 and supports the part 63 and through it and the part 58 steadies the carrier 31 and maintains it in alinement with reference to the member 30. In the disk member 56 are set two pins or studs 65 whose conical heads project downward therefrom 180 degrees apart, and in the part 63 are set two similar pins or studs 66 whose heads extend up through holes in the "bottom" of the cup-like part 58 so that their conical upper ends may upon occasion engage the heads of

the studs 65. The lower edge of the cup 62 is knurled at 67 to afford a good hold for the hand in screwing it up and down on the member 30 to raise and lower the studs 66, its range of movement downward being limited by a portion of the casing of the switch 40. Obviously the manipulation and adjustment of the parts 62 and 66 does not in the least interfere with simultaneous running of the fans 45 and revolution of the carrier 31.

When the fans 45 are started up, they will swing outward as already described and turn the disk or collar 56 until the studs 65 thereon come against the studs 66 on the part 63. By raising the studs 66, the swing permitted the fans 45 before this happens will be shortened (owing to the conical form of the heads of the studs 65 and 66) and the normal carrier speed increased, while by lowering said studs 66 the swing thus permitted will be lengthened and the normal carrier speed reduced. As shown, the studs 66 are in substantially their highest running position, corresponding, say, to a normal speed of 30 R. P. M. for the carrier. By lowering them as far as possible the normal carrier speed may be made 10 R. P. M., say. By screwing the cup member 62 far upward on the member 30 from its high speed position so as to lift the pins 66 against the collar 56 and lift the collar 56 till the heads of its screws 61 jam against the lower side of the bearing part 33, the carrier 31 can be frictionally locked stationary with the fans 45 in their positions corresponding to the maximum carrier running speed; and after this is done the carrier may be swung around by hand in spite of the friction to bring the fans to any desired positions.

It will be seen that the key 59 by which the part 58 is held fast in the hub 32 is in the form of a screw with a reduced inner end portion in a hole in said part 58: When the machine is set up and tested in the factory, the screw 59 will be used as a set screw until the proper position of the part 58 in the hub 32 for the desired speed range of the carrier 31 is found, and then the hole will be drilled in the spot thus determined and the screw 59 screwed home in it. Obviously the collar or disk 56 connected to the fans 45 is of service as a means for causing them to move in unison as well as for limiting their centrifugal movement and for speed adjustment.

It has already been mentioned that the fans 45 with their motors 56 are mounted on trunnions so that they may be tilted in the brackets 48. I have observed that in addition to their propeller action on the air the fans 45 also exert a sort of paddle wheel action, which is the greater the greater the helical pitch of their blades. Owing to this

paddle wheel action and the consequent reaction, there is a moment due to the blades of each fan 45 when below the fan axis 52 that tends (the direction of rotation of the fan being clockwise) to rotate the carrier 31 in the same direction as does the propeller action of the fan, and there is a moment due to the blades when above the axis 52 that has exactly the opposite tendency. When the fan axis 52 is horizontal, as shown in Fig. 5, these moments exactly balance one another, since the distance of the fan blades from the carrier axis 30 is the same above and below the fan axis 52, so that the lever arms of the paddle wheel reactions in these two cases are equal. When, however, the fan axis 52 is tilted downward, the lever arms of these paddle wheel reactions become unequal and there is an unbalanced paddle wheel moment opposing the propeller action of the fan. If the tilt of the fan axis 52 is considerable and the acceleration of the fan 45 at starting is very rapid (as is especially apt to be the case with a direct current electric fan), the paddle wheel moment may prevail over the propeller moment and the carrier 31 may start off and continue to rotate in the reverse of its intended direction. Ordinarily this is undesirable, for under this condition of running increase in the carrier speed may not diminish the torque on the carrier 31, but may even increase it, owing to the fact that the fan blades act on air that is more nearly stationary. The backward running can be obviated by reversing the direction of rotation of the fans 45 so that the paddle wheel moments shall reinforce the propeller moments; but this remedy still leaves the paddle wheel moments practically unregulated.

I have found that dominance of the paddle wheel moments and backward running of the carrier 31 may be avoided by any means which will prevent the carrier from getting started backward, since if the fans 45 once have time to swing around into their normal starting positions, the propeller moments will prevail over the paddle wheel moments. As shown in Figs. 6 and 8, I have provided one or more dog-like stops 68 pivoted at 69 in slots in the lower side of the bearing part 33. When the carrier 31 rotates in the right direction, the ends of these dogs 68 slide freely on the upper surface of the part 60 and over the fillister heads of the screws 61; but if the carrier 31 starts to rotate backward, the heads bring up against said dogs and stop it.

The machine last described involves no springs, the speed adjustment being effected entirely by stops. While this mode of adjustment will give as low a minimum speed and as great a range of adjustment as will

usually be desired, an even lower minimum speed can be obtained by employing spring means in aid of centrifugal force to throw the fan 45 outward from starting position. As shown in Fig. 9, there are two helical tension springs 70 connected between the screws 61 (which are made longer than shown in Fig. 8 and appropriately headed) and the pivot portions at the inner ends of the connecting rods 55. These springs 70 are not strong enough to prevent the fans 75 from assuming their starting positions, but they hasten their outward movement under centrifugal force and make their final position of equilibrium one where the torque and speed of the carrier are less than they would otherwise be.

The construction shown in Fig. 10 allows gravity to be employed in aid of centrifugal force (in lieu of the springs 70 or in addition to them) when a very low minimum carrier speed is desired. As here shown, the conical ended pivot pin 49 at the lower side of the lug 47 is replaced by a steel ball 75 seated in the conical socket in the lower side of the fork at the end of the arm 43 and engaging in a similar socket in said lug. The pivot pin 76 is made with its end portion 77 eccentric to the axis of the screw portion, so that the axis formed by the parts 75 and 77 is not vertical but slightly inclined with reference to the vertical and to the carrier axis 30. To make the minimum speed of the carrier 31 as low as possible, the pivot pin 76 is secured by its set screw 78 with its end portion 77 in about the position indicated by the dotted circle 77 in Fig. 7, so that gravity will tend to swing the fan 45 and its associated parts outward toward the position where the fan shaft 52 would be radial with reference to the carrier axis 30.

What I claim as new and desire to secure by Letters Patent of the United States, is:—

1. A fan machine comprising a revolving carrier, a rotary fan adapted through its action on the air to produce a torque thereon, and means for varying the torque controlled by the speed of revolution of the carrier.

2. A fan machine comprising a revolving carrier, a rotary fan adapted through its action on the air to produce a torque thereon, and means controlled by the speed of revolution of the carrier independently of the speed of rotation of the fan for varying and controlling the torque produced by the fan so that the same shall be high when the fan is started into action and shall be reduced after the carrier has been brought into revolution and gathered speed.

3. A fan machine comprising a revolving carrier, a rotary fan adapted to produce a torque thereon, and means controlled by centrifugal force due to the revolution of the carrier for varying the lever arm of the re-

- action due to the air blast produced by the fan so that the initial torque when the fan is started into action shall be reduced after the carrier has been brought into revolution 5 and has gathered speed.
4. A fan machine comprising a revolving carrier, a rotary fan adapted to produce a torque thereon, and means controlled by the speed of revolution of the carrier independently of the speed of rotation of the fan for shifting the axis of the fan with reference to the carrier so as to diminish the torque as the carrier gathers speed after the fan is started into action.
- 15 5. A fan machine comprising a revolving carrier and a rotary fan adapted to produce a torque tending to revolve the carrier movably mounted thereon in such wise that when it is started into action the reaction of the 20 air causes it to assume a position in which the torque is high, and that as the carrier is brought into revolution and gathers speed it moves under the resulting centrifugal force into a position where the torque is less.
- 25 6. A fan machine comprising a revolving carrier and a rotary fan pivotally mounted thereon so as to swing, under the reaction of the air and in response to variation in the rate of revolution of the carrier, about an 30 axis eccentric to that of the carrier and to its own center of gravity.
7. A fan machine comprising a revolving carrier and a rotary fan pivotally mounted thereon so as to swing, under the reaction of the air and centrifugal force, about an axis 35 extending in the same direction as that of the carrier but eccentric thereto and to its own axis and center of gravity.
8. An electric fan machine comprising a 40 multiple armed carrier mounted for revolution about an upright axis, a supporting bracket pivoted to each arm of the carrier so that it may swing horizontally to a limited extent, a rotary fan with an electric motor for driving it adjustably mounted on each bracket with its axis eccentric to the pivot, and means connected to said brackets for causing them to swing in unison.
9. A fan machine comprising a revolving 45 carrier and a rotary fan adapted to produce a torque tending to revolve the carrier movably mounted thereon in such wise that when it is started into action the reaction of the air causes it to assume a position in which the torque is high, and that as the carrier is brought into revolution and gathers speed it moves under the resulting centrifugal force into a position where the torque is less, and means for limiting the centrifugal 55 movement, said means being adjustable to vary the final, normal speed of revolution of the carrier for a given speed of rotation of the fan.
- 60 10. An electric fan machine comprising a multiple armed carrier mounted for revolution about an upright axis, a rotary fan with an electric motor for driving it pivotally mounted on each arm on an axis eccentric to its own axis and center of gravity so that it may swing horizontally outward from an inner position where the torque on the carrier produced by the fan is high into positions of successively diminishing torque, a member coaxial with the carrier and means connecting said member with both fans and motors so as to cause them to swing in unison, and adjustable means for limiting the movement of said member and the outward swing of the fans and motors.
11. A fan machine comprising a revolving 8 carrier and a rotary fan pivotally mounted thereon on an axis extending in the same general direction as that of the carrier but eccentric thereto and to its own axis and center of gravity, and so inclined with reference to the carrier axis that centrifugal force and gravity tend to swing the fan in the same direction about the pivotal axis.
12. A fan machine comprising a revolving carrier, a rotary fan pivotally mounted 9 thereon on an axis extending in the same general direction as that of the carrier but eccentric to the carrier axis and to its own axis and center of gravity, said fan being tilttable with reference to the carrier axis, and means for preventing starting of the carrier except in one direction.
13. The combination with a rotatable supporting member, of a rotatable fan disposed thereon to effect rotative movement of said member and means for maintaining a predetermined velocity of revolution without the use of a mechanical brake.
14. The combination with a rotatable supporting member, of a rotatable fan disposed thereon to effect rotative movement of said member, and means for maintaining a predetermined velocity of revolution by varying the actuating torque.
15. The combination with a rotatable supporting member, of a rotatable fan disposed thereon to effect rotative movement of said member, and means for maintaining a predetermined velocity of revolution by automatically varying the actuating torque in response to changes in the rotative speed of the fan.
16. The combination with a rotatable supporting member, of a rotatable and tilttable fan disposed thereon to effect rotative movement of said member, of means for automatically maintaining a predetermined velocity of revolution within certain limits, irrespective of the velocity of rotation and the angle of tilt of said fan.
17. The combination with a rotatable supporting member, of a rotatable fan disposed thereon and adapted to effect rotative move-

ment of the said supporting member, and resilient means for regulating the driving torque which determines the velocity of revolution of the said member.

5 18. The combination with a rotatable supporting member, of a rotatable fan pivotally supported upon the said member and adapted to be pivotally moved thereon by centrifugal force during the rotation of the said 10 supporting member, and means for limiting the degree of such pivotal movement of the said fan.

15 19. The combination with a rotatable supporting member, of a plurality of fans pivotally supported on the said member, and means for causing the said fans, when piv-

otally moved, to move for equal times and through equal distances.

20. The combination with a rotatable supporting member, of a rotatable fan disposed thereon and adapted to effect rotative movement of the said supporting member, and spring-controlled means for regulating the driving torque impressed upon the said supporting member to cause the said member 25 to rotate at a predetermined speed.

In witness whereof, I have hereunto set my hand this 8th day of Sept., 1914.

EDWARD T. SHAW.
